UNITED STATES PATENT OFFICE.

GOTTHILF ANSGARIUS BETULANDER, OF SODERTORNS VILLASTAD, SWEDEN, AS-
SIGNOR TO THE RELAY AUTOMATIC TELEPHONE COMPANY, LIMITED, OF LONDON,
ENGLAND.

INTERCONNECTION OF ELECTRICAL LINES.

Application filed August 11, 1922. Serial No. 581,179.

To all whom it may concern:

Be it known that I, GOTTHILF ANSGARIUS BETULANDER, a subject of the King of Sweden, and resident of Sodertorns Villastad, Sweden, have invented a new and useful Improvement in the Interconnection of Electrical Lines, of which the following is a specification.

The invention relates to relay switches for interconnecting electrical lines, particularly subscribers' lines and junction lines in telephone plants.

The object of this invention is to provide switching apparatus which shall be simpler in operation than those hitherto proposed and more flexible, that is, more readily adapted to changing conditions of traffic.

The invention is illustrated by the accompanying drawings, in which Figure 1 shows the general scheme of a known arrangement, Figure 2 is a diagram illustrating that arrangement, Figure 3 is a diagram showing the arrangement according to the present invention in which each of certain outgoing lines is connected to all the sets of contacts of the switch, while Figure 4 shows a modification of the arrangement according to the present invention in which more than one outgoing line is connected to each set of contacts.

Figure 5 shows the circuit for the arrangement shown in Figure 3. Figure 6 shows a modification of the arrangement shown in Figure 5.

Figure 1 of the accompanying drawings shows the general scheme of a known switching arrangement for interconnecting lines by means of relays. In such schemes it is generally required that connections may be established between two groups of lines G^1 and G^2 in such a manner that each line AL of one group may have access to any line FL of the other group. It may be assumed as an example that group G^1 comprises 100 subscribers' lines and that group G^2 comprises, for instance, 10 junction lines in an automatic telephone exchange. The small circles at the crossing points of the different lines then represent the means by which the lines are connected together. When using simple relays for effecting the connections, either one relay may be provided at each connecting point, the number of relays being then equal to the product of the numbers of the lines in each group, or relay switches

made up of a smaller number of operative windings may be used in which case the windings are arranged to be energized in different combinations in a known manner, each connection being effected by the combined action of, for instance, two windings. A switch of the kind last mentioned is schematically illustrated in Figure 2. For practical reasons the contacts for interconnecting the lines must be arranged on a plurality of such switches, so that in an arrangement according to Figure 1 the subscribers' lines are divided in ten sub-groups UG^1 , UG^2 , UG^3 , each including ten lines and one switch being assigned to each sub-group. Ten switches are therefore required for effecting all connections. The sets of contacts KG enclosed by chain lines in Figure 1 will then belong to different switches of the kind shown in Figure 2.

In Figure 2 the lines AL and FL are drawn in chain lines. Each set of contacts is represented by two contact springs, the lower of which is adapted to be operated by a corresponding arm a extending from a rod 80 A pivotally mounted along the corresponding horizontal row. The arms a are normally inoperative and may be caused to actuate the corresponding sets of contacts by means of arms m extending from vertical, 85 pivotally mounted rods M . The rods M and A are provided at their ends with armatures adapted to be operated by electromagnets MR and AR , the rods being thereby turned in the direction of the arrows. 90 The selection and operation of the different sets of contacts is effected by energizing the magnets MR and AR in different combinations in the following manner. If, for instance, the contact KG^{31} is to be operated, 95 the magnets MR^1 and AR^3 will be energized, the magnet MR^1 being first caused to operate and then magnet AR^3 . Rod M^1 is thereby turned so as to bring its arms m into operative position beneath the different sets 100 of contacts of the corresponding vertical row, and the arms a of the appertaining rod A^3 are then turned upwards. The arm a corresponding to the contact set KG^{31} then actuates the corresponding arm m of the rod 105 M^1 so that the lower contact spring is brought into contact with the upper contact spring. Thus connection is established between lines AL^1 and FL^3 . Immediately after the connection has been effected mag- 110

net MR^1 is deenergized whereupon rod M^1 is returned to its normal position by the action of a spring and consequently all arms m are returned except that one beneath the contact set KG^{31} , which arm is retained in operative position by the action of arm a . This is rendered possible by arms m being either pivotally connected to rod M or made of elastic wires or the like. Disconnection 10 is effected by deenergizing magnet AR^3 , arm m then resuming its normal position. If lines AL^2 and FL^2 are to be connected together this is effected in a similar manner by energizing magnets MR^2 and AR^2 . It 15 will be seen from the above that by the operation of two members A and M crossing each other, only the set of contacts located at the crossing point of the corresponding horizontal and vertical rows will be operated. 20 The present invention contemplates the use of relay switches of the kinds described in a new manner in respect of the connection of the switches to the lines to be connected. The invention is schematically illustrated 25 in Figure 3 in which the lines and the switches are shown in a manner analogous to Figure 1.

In relay switching systems as hitherto carried out, for instance, the system shown 30 in Figure 1, there are in each switch as many incoming and outgoing lines as there are vertical and horizontal rows of contact sets respectively, each line having consequently only one row of contact sets in each switch. 35 According to the present invention, however, the sets of contacts pertaining to each line of one line group (incoming or outgoing lines), are distributed over a plurality or, if wanted, over all rows of contacts of the 40 switch. Figure 3 shows the arrangement when each outgoing line FL is connected to all sets of contacts of the switch, there being then as many switches as there are lines in the group G^2 of outgoing lines. This alteration 45 of the connection of the switches has for its object partly to simplify the switching apparatus and circuits controlling the switching operation, partly to make the lines more independent of one another so as to facilitate the shifting of the switches 50 from one line group to another according to the variations of the traffic for the purpose of better utilizing the switches. It has the additional advantage when used with 55 switches, such as are shown in Figure 2, in which the contact groups are rigidly mounted, that the number of trunks can be varied readily.

In the arrangement shown in Figure 1 to 60 decrease the number of trunks would leave contacts unused, and to increase the number of trunks would require structural alteration of the switches.

In the arrangement shown in Figure 3 65 variation in the number of trunks can be

effected by increasing the number of switches.

If wanted two or more of the switches shown in Figure 3 may be built together into one switch with common operating mechanism. Figure 4 shows such an arrangement in which the sets of contacts pertaining to two outgoing lines are brought together in a single multiple, the number of switches being then half the number required in Figure 3, whereas the capacity of each switch will be twice as large. 75

It should be observed that the invention is not limited to the use of switches of the particular construction shown in Figure 2. It is only essential that the sets of contacts should be arranged in intersecting rows and that the members for selecting and operating the sets of contacts should be arranged along these rows in such a manner that by 80 operating two intersecting members only the set of contacts located at the point of intersection of the corresponding rows will be operated. Otherwise the construction of the operating mechanism may be modified in 85 many ways, for instance, by arranging each rod M in common to several vertical rows, the rod being then adapted to be set into 90 one of several positions.

Figure 5 shows the circuits for an arrangement according to Figure 3. Two outgoing junction lines FL^1 and FL^2 and appertaining switches RV^1 and RV^2 are represented. Only such parts of the switches are shown as are required for establishing connections with four subscribers' lines AL connected to two vertical rows of the switches. The circuits of the marking and connecting relays MR and AR of all switches are controlled by a common switching device comprising a searcher RS , switching relays OR and auxiliary relays SR and TR . The circuits of the marking and connecting relays are also carried over contacts of group relays GR^1 , GR^2 , assigned to the different switches, the arrangement being such that the marking and connecting relays of each switch can only be operated when the corresponding group relay GR is energised. The operation is as follows:— 100

Upon a call occurring, for instance, on subscriber's line AL^1 , a circuit 1 is closed over the subscriber's line and through its line relay LR^1 . The latter energizes and closes a circuit 2 through the first relay PR^1 of the searcher RS and over contacts k^1 of the connecting relays of the first switch, provided the first junction line FL^1 is disengaged at the time. 105

If this line should be engaged, one of the appertaining connecting relays AR will be energized and the corresponding contact k^1 be open, circuit 2 being then closed through the second relay PR^2 of the searcher (provided the second junction line FL^2 is dis- 110

125

130

engaged), or through some other relay PR¹ not shown in the drawing, which corresponds to a disengaged junction line FL.

- Upon relay PR¹ energizing a circuit 3 is closed through group relay GR¹ which operates and connects itself into a holding circuit over its contact k⁸. Relay GR¹ also closes circuit 4 through switching relay OR¹ which cuts into circuit relay OR². When relay OR¹ energizes the searcher is shifted at the contacts k⁴ from the test wires PL of the injunction lines to lines RL which serve to mark the presence of calls on lines pertaining to the different sets of vertical 15 rows of the switches, by the said lines RL being connected to earth over contacts on the line relays LR. As the calling subscriber's line is connected in this instance to the first vertical rows, a circuit 5 is completed through the relay PR¹ of searcher RS said relay now closing circuit 6 through marking relay MR¹ pertaining to the first vertical row. The latter relay energizes 20 and receives holding current over circuit 7 which includes switching relay OR³. OR³ operates and immediately cuts in relay OR⁴. By the operation of relay OR³ searcher RS is shifted at contact k⁵ to lines SL which serve to mark (by the closure of contacts 25 of the line relays LR) the presence of calls among the lines connected to a separate vertical row of contacts. Suppose line AL¹ to be the only calling line of those connected to the same vertical row, circuit 8 will 30 be completed through relay PR¹ of the searcher. This relay will now close circuit 9 through one winding AL of the first connecting relay AR¹ and through relay SR. Relay AR¹ energizes to establish connection 35 between subscriber's line AL¹ and junction line FL¹ through contact set KG¹. At the same time by the connection of the subscriber's line to relay FR¹ in the junction line circuit 10 was closed through relay FR¹. This relay in turn closes holding 40 circuit 11 for connecting relay AR¹ through the winding HL of this relay and through the subscriber's cut-off relay UR¹. The latter cuts off line relay LR¹ in the usual 45 way.

The circuit which operated connecting relay AR¹ initiated the disconnection of the common switching device by relay SR closing circuit 12 for slow release relay TR¹ 50 which cuts in slow release relay TR². The latter opens the holding circuit for group relay GR¹ which then de-energizes and cuts off relay MR¹, relays OR¹ and relay SR. The common switching device is thus prepared 55 for effecting another call.

If two calls should occur simultaneously on lines pertaining to different vertical rows, circuit 5 will at first be branched through both relays PR¹ and PR² of the 60 searcher. As the first relay PR¹ opens at

once the circuit of the second relay PR² it is evident that only the calling line of the first vertical row will obtain connection, whereas the other calling line has to wait till the first connection has been effected. 70 If two calls occur simultaneously among lines pertaining to the same vertical row, the circuit 8 will at first be branched similarly through both relays PR¹ and PR². As previously explained only the first relay 75 PR¹ remains operative and consequently one call will be effective before the other and double connection will thus be prevented.

As seen from the foregoing description the common searcher RS has for its object partly to select a disengaged junction line and partly to prevent double connections when several calls occur simultaneously. Figure 6 shows a modification of the arrangement of Figure 5, in which these 80 operations are effected by the marking relays of the relay switches and by the line relays of the subscribers' lines whereby the common searcher may be dispensed with. The selection of a disengaged junction line 85 by means of the marking relays MR is rendered possible according to the arrangement shown in Figure 6 by these relays being directly inserted in the test circuits of the corresponding junction lines, which circuits 90 include the breaking contacts k¹, k², etc., of the connecting relays, and by the marking relays mutually controlling their circuits in a similar manner to that in which 95 relays PR control each other's circuits. 100

Upon a call on the line AL¹, for instance, line relay LR¹ is operated as before and (supposing the first junction line to be disengaged) circuit 13 is completed through the appertaining marking relay MR¹ of the 105 first relay switch and through a relay RR common to the whole group of subscribers. If at this moment also the second junction line is disengaged, a short current impulse is simultaneously obtained through marking relay MR¹ of the second relay switch, said impulse, however, being immediately interrupted at contact k⁶ upon relay MR¹ of the first relay switch energizing. It will consequently have no influence on the 110 switching operation. The first relay MR¹ closes circuit 14 through one winding of connecting relay AR¹ which is at once connected into holding circuit 15. At the same 115 time also the connecting relays AR¹ of the other relay switches are operated (provided said relays have not been previously energized). As, however, at the time no marking relay is operated in the other 120 switches, no connection is effected in these switches. When the marking relay of the first switch energizes and the calling line shall have become connected to relay FR¹ a holding circuit 16 is closed over the third 125 wire and through the subscriber's cut-off 130

relay UR¹ which cuts off line relay LR¹. At the same time circuit 13 for relay RR and marking relay MR¹ is opened at contact k¹ of AR¹ and as a consequence the temporary holding circuits 15 of all connecting relays AR¹ are opened. After that only the connecting relay AR¹ of the first switch is maintained in operative position. The switching devices are now again ready for effecting another connection.

If calls should occur simultaneously on lines AL¹ and AL², line AL¹ will first be connected owing to the corresponding line relay LR¹ opening the circuit of connecting relay AR² at its contact k⁷ simultaneously with the closing of circuit 14 of connecting relay AR¹. Similarly relay LR² opens the circuit of the next connecting relay and so on. Thus when several calls occur simultaneously in the same sub-group UG, only one connecting relay AR will be operated at a time and double connections are therefore prevented.

The same result is obviously attained if the line relays LR of each sub-group UG mutually control their circuits in a manner analogous to the control of the circuits of the relays PR of the searcher RS, Figure 5.

If calls occur simultaneously on the lines AL¹ and AL¹¹, that is, on lines pertaining to two different sub-groups UG¹ and UG² or two different vertical rows of the switches, only marking relay MR² pertaining to sub-group UG² will operate owing to the relay last mentioned opening the circuit of relay MR¹ at its contact k⁸. Similarly the circuit of marking relay MR² would be carried over a back contact of the next marking relay and so on, the marking relays thus mutually controlling each other's circuits in the same way as the relays PR of the searcher RS, Figure 5. When calls occur simultaneously in several sub-groups or vertical rows, the calls will therefore be effected successively in the order in which the corresponding marking relays are connected, so that in this case also double connections are prevented.

What I claim is:—

1. The combination of a plurality of lines of one order, a plurality of lines of a second order, a plurality of sets of contacts, the contacts of each set being arranged in intersecting rows and columns, each line of the second order being connected to only one set of contacts but to more than one row of contacts in that set and each line of the first order being connected to as many contacts in each of the sets as there are lines of the second order connected to that set, a relay adapted to control each row of each set and a relay adapted to control each column of each set.

2. The combination of a plurality of lines of one order, a plurality of lines of a second

order, a separate set of contacts connected to each line of the second order, the contacts of each set being arranged in intersecting rows and columns, each line of the first order being connected to only one contact of each set, a relay adapted to control each row of each set and a relay adapted to control each column of each set.

3. The combination of a plurality of lines of one order, a plurality of lines of a second order, a number of sets of contacts, the contacts of each set being arranged in intersecting rows and columns, each line of the second order being connected to only one set and each line of the first order being connected to as many contacts of one column of each of the sets as there are lines of the second order connected to that set, a relay adapted to control each row of each set and a relay adapted to control each column of each set.

4. The combination of a plurality of lines of one order, a plurality of lines of a second order, a plurality of sets of contacts, the contacts of each set being arranged in intersecting rows and columns, each line of the second order being connected to only one set of contacts and each line of the first order being connected to as many contacts of each of the sets as there are lines of the second order connected to that set, a relay adapted to control each row of each set, a relay adapted to control each column of each set, a line relay associated with each line of the first order, and means whereby the line relays control the circuits of the relays controlling the various rows of the various sets.

5. The combination of a plurality of lines of one order, a plurality of lines of a second order, a separate set of contacts connected to each line of the second order, the contacts in each set being arranged in intersecting rows and columns, each line of the first order being connected to only one contact of each set, a relay adapted to control each row of each set, a relay adapted to control each column of each set, and means whereby only one of the last mentioned relays can operate or remain in operative position at any instant.

6. The combination of a plurality of lines of one order, a plurality of lines of a second order, each line of the second order comprising three wires, a plurality of sets of contacts, the contacts of each set being arranged in intersecting rows and columns, each line of the second order being connected to only one set of contacts and each line of the first order being connected to as many contacts of each of the sets as there are lines of the second order connected to that set, a relay adapted to control each row of each set and a relay adapted to control each column of each set, the last mentioned

relays being inserted in the third wires of the lines of the second order.

7. The combination of a plurality of lines of one order, a plurality of lines of a second order, each of the lines of the second order comprising three wires, a separate set of contacts connected to each line of the second order, the contacts of each set being arranged in intersecting rows and columns, ¹⁵ each line of the first order being connected

to only one contact of each set, a relay adapted to control each row of each set and a relay adapted to control each column of each set, the last mentioned relays being inserted in the third wires of the lines of the ¹⁵ second order.

In testimony that I claim the foregoing as my invention I have signed my name this 18th day of July 1922.

GOTTHILF ANSGARIUS BETULANDER.
